UNITED STATES PATENT OFFICE

EUGENE PRONDECKE, OF MILLERS FALLS, MASSACHUSETTS

DESIGN FOR A RADIATOR OR SIMILAR ARTICLE

Application filed January 6, 1932. Serial No. 42,392. Term of patent 7 years.

To all whom it may concern:

Be it known that I, EUGENE PRONDECKE, a citizen of the United States, residing at Millers Falls, in the county of Franklin and State of Massachusetts, have invented a new, original, and ornamental Design for Radiators or Similar Articles, of which the following is a specification, reference being had

to the accompanying drawing, forming part hereof.

The figure is a perspective view of a radiator showing my new design.

I claim:

The ornamental design for a radiator or similar article as shown.

EUGENE PRONDECKE.
